(57) **CLAIM**

The ornamental design for a hand tool, as shown and described.

DESCRIPTION

FIG. 1 is a side elevation of a hand tool showing our new design, all other side elevations being identical, FIG. 2 is a top plan view thereof; and, FIG. 3 is a bottom plan view thereof.

The stippling in FIG. 1 denotes a colored finish. The non-stippled portion of the hand tool denotes a metallic finish.
